UNITED STATES PATENT OFFICE.

STACY BOWMAN, OF CURWENSVILLE, PENNSYLVANIA.

RAIL-JOINT.

1,100,210.

Specification of Letters Patent. Patented June 16, 1914.

Application filed November 26, 1913. Serial No. 803,214.

To all whom it may concern:

Be it known that I, STACY BOWMAN, a citizen of the United States, residing at Curwenville, in the county of Clearfield and State of Pennsylvania, have invented a new and useful Rail-Joint, of which the following is a specification.

The present invention appertains to a rail joint, and aims primarily to provide a novel and improved means for coupling or connecting the meeting ends of railroad rails.

It is the object of the present invention to provide a unique means for coupling or connecting the meeting ends of the rails, and which shall be comparatively simple, compact, substantial, durable and inexpensive in construction, as well as simple, convenient, practical and efficient, in its use.

It is also the object of the present invention to provide a joint of the nature indicated, which will permit the rails to expand and contract under the atmospheric changes, and which will also permit the rails to swing slightly with respect to one another, in the longitudinal vertical plane of the rails.

A still further object of the present invention is to provide a rail joint dispensing with the employment of the usual fish plates and bolts, and which is of such construction as to enable the spikes to connect the rails to the coupling member, as well as locking the rail ends and coupling member to the tie.

With the foregoing general objects outlined and with other objects in view, which will be apparent as the nature of the invention is better understood, the present invention resides in the combination and arrangement of parts and in the details of construction hereinafter described and claimed, it being understood that changes in the precise embodiment of the invention herein disclosed can be made within the scope of what is claimed without departing from the spirit of the invention.

The present invention has been illustrated in its preferred embodiment in the accompanying drawing, wherein:

Figure 1 is a plan view of a rail joint constructed in accordance with the present invention. Fig. 2 is a side elevation of the joint. Fig. 3 is a longitudinal section of the joint, taken on the line 3—3 of Fig. 1. Fig.

4 is a cross section taken on the line 4—4 of Fig. 3. Fig. 5 is a perspective view of the coupler.

In the drawing, a pair of rails are designated by the numerals 1. In carrying out the present invention, a pair of plates 2 are welded, brazed or otherwise attached to the opposite sides of the web of each rail, at the meeting ends of the rails, the end portions of the rail webs being cut away, as at 3, to provide a socket in the end of each rail, below the tread or ball of the rail, and opening downwardly and longitudinally. The plates 2 being attached to the webs of the rails, in reality constitute portions of the webs, the adjoining ends of the plates 2 being flush 70 with the ends of the treads or balls of the rails.

The meeting ends of the treads or balls of the rails are provided with depending lugs 4 within the sockets 3 or it may be said, that the upper walls of the sockets are provided with the lugs 4, which define the supplemental recesses or sockets 5 at the corners between the upright and top walls of the sockets or recesses 3. The recesses or cut away portions 5 may be readily formed in the ends of the rails, prior to the attachment of the plates 2 to the rails, as will be obvious. The plates 2 are provided at their lower ends with flanges 6, and the terminal portions of the base flanges of the rails are cut away below the free or adjoining portions of the flanges 6.

The coupler embodies an upstanding web 7 which is receivable by the recesses or cavities 3, and is provided with the base flanges 8 adapted to rest upon the cross tie. The end portions of the base flanges of the rails being cut away, will accommodate the base flanges 8 of the coupler, whereby the bottoms of the rails and coupler will be flush. The flanges 6 of the plates 2, which in reality constitute portions of the base flanges of the rails, are designed to overlap the base flanges 8 of the coupler, 100 and the side edges of the coupler base flanges are provided with upturned flanges or lips 9 with which the edges of the flanges 6 are engageable to maintain the rail ends and coupler against lateral displacement.

The web 7 is provided with upstanding lugs 10 at its ends, which are engageable in the sockets or cavities 5, and which form

a depression or notch 11 therebetween adapted to receive the lugs 4 of the rails, as clearly seen in Fig. 3.

The flanges 6, and the base flanges 8 of the coupler are provided with registering or coinciding longitudinally elongated slots 12, for the reception of the spikes for spiking the rail ends and coupler to the cross tie, in a manner which will be clearly apparent, without illustration or further description.

In practice, the coupler 7—8 may be readily set or placed upon the tie, at the proper position, and the ends of the rails 15 may be readily placed over the web 7 of the coupler, whereby the lugs 4 and 10 of the rails and coupler will interengage or interlock, and whereby the free portions of the flanges 6 will overlap the base flanges 20 8 of the coupler, within the lips 9. The base flanges of the rails and the base flanges of the coupler are designed to rest snugly upon the tie or ties, and the spikes may be readily passed through the registering 25 slots or openings 12 to take into the tie for holding the joint against displacement.

The construction of the interfitting parts is such, as to permit the rail ends to slide longitudinally for a limited extent, under 30 changes in atmospheric conditions, the interlocking lugs 4 and 10 of the rails and coupler, respectively, preventing the rails from being accidentally uncoupled. It is also possible to swing the rails vertically 35 with respect to one another, for a limited extent when desired upon a curved roadbed. The rails may be detached by simply with-

drawing the spikes, in which event the rail ends may be lifted off of the coupler 7.

From the foregoing, the several advantages of the present invention will be obvious to those skilled in the art, it being noted that the objects have been carried out satisfactorily, and that the present joint is such, as to withstand the hammering and jarring which joints of this character are subjected to in use.

Having thus described the invention what is claimed as new is:—

In a rail joint, the combination with the meeting ends of the rails, of plates secured to the sides of the webs of the rails at the meeting ends thereof, the terminal portions of the webs and base flanges of the rails being cut away to provide downwardly and longitudinally opening recesses, and a coupler embodying a web designed to fit in the said recesses and having base flanges to rest on the tie, the cut away portions of the base flanges of the rails accommodating the base flanges of the coupler, the said plates having lower flanges to overlap the base flanges of the coupler, and the base flanges of the coupler having upturned side lips to engage the edges of the flanges of the said plates.

In testimony that I claim the foregoing as my own, I have hereto affixed my signature in the presence of two witnesses.

STACY BOWMAN.

Witnesses:

SELINA WILLSON,
I. E. SIMPSON.
